UNITED STATES PATENT OFFICE.

ISIDOR ABRAMS, OF NEW YORK, N. Y.

COIN-RECEIVER FOR NEWSPAPER-STANDS.

1,232,160.

Specification of Letters Patent.

Patented July 3, 1917.

Application filed February 21, 1917. Serial No. 150,077.

To all whom it may concern:

Be it known that I, ISIDOR ABRAMS, a citizen of the United States, and resident of New York, borough of Brooklyn, in the county of Kings and State of New York, have invented a certain new and useful Coin-Receiver for Newspaper-Stands, of which the following is a specification.

The object of this invention is to provide a receiver for coins to be used in connection with newspaper stands wherein the purchaser may deposit his coin.

It has become a practice with newspaper dealers to display the papers on a stand in front of their store and in most cases are left without an attendant. It is also the practice of most people when purchasing a newspaper, to take it themselves and to leave the coin on the stand. In many cases the money is stolen before the dealer gets outside of his store. I overcome this objectionable feature by using a box having a grating at its top for receiving the coins, which is adapted to be locked to the stand. The bars in the grating are spaced close enough to prevent any one from getting the coins within the box and wide enough to permit the coin to drop freely into the box. The bars are also inclined so that a coin dropped on top will readily slide down into the box, instead of being retained on top.

The advantage of using a grating instead of a slot for depositing the coin, is that in most cases purchasers of newspapers would not take the trouble of depositing the coin in the slot, while with the grating, all that they have to do is to drop the coin on top of the grating and the coin will slide into the box. Another advantage of my device is that the box serves as a cover for the newspapers to protect them in rainy weather. A further advantage of my device is, that it is simple and inexpensive.

Other features of my device will be apparent from the detailed description and the accompanying drawing forming a part of this specification and in which similar numerals refer to similar parts in all the views, and in which:

Figure 1 is a front elevation of a newspaper stand showing my device in position; Fig. 2 is a section taken on line 2-2 of Fig. 1; Fig. 3 is a section taken on line 3-3 of Fig. 1; Fig. 4 is a portion of a section taken on line 4-4 of Fig. 1; Fig. 5 is a portion of a section taken on line 5-5 of Fig. 3;

and Fig. 6 is a section taken on line 6-6 of Fig. 1 but showing a modified method of locking the coin box to the stand.

Referring to the drawing, the stand consists of the sides 1, the back 2 and the boards 3 and 4, the board 3 generally serving as a brace and the board 4 serving as a shelf upon which the newspapers are deposited. The stand is preferably made of wood. A slat 5 is generally fixed to the back 2 as shown, and is used to hold the newspapers in a vertical position. The coin box 6 is provided with legs 7 which are adapted to rest on the shelf 4 and the box is thereby supported. The bars 8 preferably inclined as shown, are fixed near the top of the box 6 forming a grating which will permit the dropping of coins into the box but will prevent any one from getting them. A slot 9 is provided in one side of the box 6, which permits the removal of the coins from the box 6, but is inaccessible when the box 6 is in position, since the side of the box 6 abuts against the side 1 of the stand. The box 6 is fixed in position by means of the bar 10, which is attached to the bottom of the box while its projecting end passes through a corresponding slot in the back 2 of the stand and is then locked by means of the lock 13 passing through the hole 11 in the bar 10. In order to reinforce the slot in the back 2, I provide the metal plate 12, having a slot therein to receive the projecting end of the bar 10, and fixed to the back 2.

A modified method of locking the coin box 6 in position is shown in Fig. 6. Instead of having the bar 10, I use a bar 14 having one end bent over as shown at 15 and the other end is provided with a hole 16 for receiving a lock. A slot is provided in each of the sides 1 of the stand, and in the side of the box 6 to permit the passing of the bar 14 therethrough. The bar 14 also passes through the slot 9. A reinforcing plate 17 for the slot in the side 1 is also provided. It will be evident from Fig. 6 that when the bar 14 is in the position shown, the coin box 6 will be locked with the stand.

In the use of my device, some of the newspapers are kept on the shelf 4 and others are displayed in a vertical position and are held by the bar 5. The gratings 8 on the top of the box 6 are left exposed so that a purchaser may drop his coin thereon. It will be evident that the box 6 also serves as

a cover for the papers placed on the shelf 4, and will protect them in rainy weather.

It will be evident that the box 6 may be supported and locked in position in many other ways than that shown, and therefore I do not wish to limit myself to the exact construction shown.

Having thus described my invention I claim as new and wish to secure by Letters 10 Patent:

1. A device of the character described, comprising a stand adapted to hold newspapers or similar articles, a coin box removably fixed to said stand, a grating at the top 15 of said box adapted to permit coins dropped thereon to fall within the box but to prevent the removal of the coins therethrough, and means for locking said box to the stand.

2. A device of the character described, comprising a stand adapted to hold newspapers or similar articles, a coin box removably fixed to said stand, a grating at the top of said box comprising flat bars placed in an inclined position and adapted to permit coins dropped thereon to slide into the box but to prevent the removal of the coins therethrough, and means for locking said box to the stand.

3. A device of the character described, comprising a stand adapted to hold newspapers or similar articles, a coin box having a slot at one side thereof for permitting the removal of coins therefrom, removably fixed to said stand so that said slot is inaccessible when the box is in position, a grating at the top of said box adapted to permit coins dropped thereon to fall within the box but to prevent the removal of the coins therethrough, and means for locking said box to the stand.

4. A device of the character described, comprising a stand adapted to hold newspapers or similar articles, a coin box having

a slot at one side thereof for permitting the removal of coins therefrom, removably fixed 45 to said stand so that said slot is inaccessible when the box is in position, a grating at the top of said box comprising flat bars placed in an inclined position and adapted to permit coins dropped thereon to slide into the 50 box but to prevent the removal of the coins therethrough, and means for locking said box to the stand.

5. A device of the character described, comprising a stand for holding newspapers 55 or similar articles, a coin box removably fixed to said stand, a grating at the top of said box adapted to permit coins dropped thereon to fall within the box but to prevent the removal of the coins therethrough, and 60 a bar for locking said box to the stand.

6. A device of the character described, comprising a stand for holding newspapers or similar articles having a slot in the back thereof, a coin box having a grating at the 65 top thereof adapted to permit coins dropped thereon to fall within the box but to prevent the removal of the coins therethrough, means for locking said box to the stand comprising a bar fixed to the bottom of said box 70 having a projecting end adapted to pass through the slot in the back of the stand and a hole within said projecting end, and a lock adapted to pass through said hole in the bar.

7. A device of the character described, comprising a stand adapted to hold newspapers or similar articles, a coin box fixed to said stand, a grating at the top of said box adapted to permit coins dropped thereon 80 to fall within the box but to prevent the removal of the coins therethrough.

Signed at Brooklyn, in the county of Kings and State of New York, this 19th day of February, 1917.

ISIDOR ABRAMS.
